UNITED STATES PATENT OFFICE.

ALFRED N. CLOUGH, OF SAN JOSE, CALIFORNIA, ASSIGNOR TO THREE LEAF COT MANUFACTURING COMPANY, OF SAN JOSE, CALIFORNIA, A CORPORATION OF NEVADA.

CONVERTIBLE FURNITURE.

1,320,365.

Specification of Letters Patent. Patented Oct. 28, 1919.

Application filed January 22, 1918, Serial No. 213,130. Renewed July 7, 1919. Serial No. 309,179.

To all whom it may concern:

Be it known that I, ALFRED N. CLOUGH, a citizen of the United States, residing at San Jose, in the county of Santa Clara and 5 State of California, have invented new and useful Improvements in Convertible Furniture, of which the following is a specification.

This invention relates to convertible structures and particularly pertains to foldable and convertible furniture.

The prime object of this invention is to provide a structure which may be easily folded into a collapsed position or unfolded 15 therefrom, and when in its set-up condition may be adapted to form various substantial articles of furniture, such as a settee, cot, or table.

In carrying out the present invention I 20 contemplate the use of parallel foldable side bars hinged at points along their length and foldably united by cross bars engaging vertically adjustable legs secured to said bars, and which are further braced by the side 25 bars. Such a structure is so designed as to receive a canvas covering and to be readily converted to form different articles of furniture in which each element of the structure will contribute a definite function in forming 30 a rigid article of the character desired.

In the accompanying drawings:—

Figure 1 shows a side elevation of the cot structure in extended position, with extension legs thereon shown in dotted lines as 35 extended to form a table.

Fig. 2 shows an end elevation of the same.

Fig. 3 shows an end elevation of the same device converted into a bench or settee.

Referring to the accompanying drawings, 40 the main frame is shown as comprising a pair of parallel side bars 10, provided at their opposite ends with T-shaped spacing plates 11 which are pivotally fixed thereto. The downwardly extending portions of 45 these plates are rigidly secured to the upper ends of supporting legs 12. Extension bars 13 are pivotally connected to the outstanding ends of the plates 11 and in the same vertical plane with the side bars 10.

50 Detachable transverse bars 14 are formed with a series of apertures 33 along one of their faces, within which pins 33' may project. These pins are fixed to and extend from the outer ends of the bars 13. A can-

vas or other flexible covering 15 is tacked 55 along opposite sides to the intermediate bars 10 and also to the extension bars 13. This canvas is formed along its marginal side edges to accommodate the plates 11 and along its ends with loops 17 to receive the 60 transverse end bars 14.

The struts or braces for the frame include transverse spacing bars 18, pivotally secured to each of the legs and adjacent to the lower ends thereof. These bars are arranged in 65 pairs connected at their adjacent ends by a knee joint or hinge 19 to permit upward folding movement. This joint is in the form of a hinge, the leaves of which abut against each other in a manner to prevent 70 the bars from assuming a horizontal aligned position when the structure is unfolded.

Intermediate the ends of each of the spacing bars 18 is attached a pivoted link 20, these links in turn being connected at their 75 inner ends by means of a U-shaped fitting forming a knee joint, the pivot pin of which is in vertical alignment with the pivot of the joint 19. These tie links are of such length that they may assist in preventing 80 the sections of the cross bar 18 from assuming a straight line when extended, as shown in Fig. 2. In some cases, however, the tie links may be eliminated and the knee-joint 19 relied upon to hold the spacing bars in 85 an angular relation to each other.

A diagonal brace bar 22 is pivotally connected to each of the legs at a point above the connection of the spacing bars 18. These bars extend inwardly and downwardly and 90 pivotally engage the spacing bars 18 at points intermediate their lengths. As particularly shown in Fig. 2, the diagonal bars 22 are formed in two sections connected by a knee-joint to permit upward folding movement. Between each leg and adjacent to the intermediate side bars is pivoted a diagonal brace member 23, knee-jointed to fold 95 upwardly and outwardly. Upon the opposite side of each leg is pivoted a similarly 100 jointed brace member 24 which extends upwardly and outwardly to pivotally engage the extension bars 13 and provide them with support.

In the case of one pair of extension bars 105 13, the braces 24 are disconnectible from the legs 12, the latter being provided with pins 25 at different points vertically therealong

to receive the disconnectible ends of the braces, it being understood that they are formed with knee-joints which prevent them from folding outwardly from the position 5 shown in Fig. 1. By this disconnectible feature of these braces the angular position of the extension frame at one end of the structure may be varied, as indicated in dotted lines in Fig. 1, to form a head or 10 back-rest for reclining purposes.

In setting up the structure the intermediate side bars and the legs secured thereto are separated. Due to the construction of the spacing bars 18 and the brace members 15 22, the intermediate bars may be drawn apart in constant parallel relation with each other. When the spacing bars 18 have moved to the position shown in Fig. 2, the legs will be in proper spaced relation to 20 each other to stretch the canvas 15 between the intermediate bars. It will be understood that before or after this operation the end bars 13 may be swung downwardly and into longitudinal alinement with the intermediate bars 10, so that a single plane will 25 be formed by the canvas covering. The opposite ends will, of course, be braced by the diagonal bracing members 24 which will also assist the brace members 23 in holding 30 the legs of the structure at right angles to the frame members. When in this position a cot will be formed and an adjustable head-rest will be provided by disposing the pivoted keepers of the braces 24 in a desired 35 relation to the openings in the brace bars which engage the pins 25.

In order that a table may be formed, the structure as assembled is adjusted to stretch and sustain the canvas covering in a single 40 plane, after which extension leg members 28 may be drawn out from between the members 12^a and 12^b constituting the main legs. The members 28 normally telescope within the main structure of the legs and 45 are guided by plates 27 securing the elements 12^a and 12^b in rigid relation to each other.

A spring-pressed pawl 29 is fitted within the upper end of each leg extension 28 and 50 is provided with a U-shaped recess 31, within which a projection 32, at the lower end of the leg members, will register. A spring 30 holds this pawl against the surface of the leg members 12^a and insures that it will 55 positively engage this recess to temporarily prevent upward or downward movement of the extensions in relation to the legs. The extended position of the legs to form a table is particularly indicated by dotted lines in 60 Fig. 2.

A bench or settee may be formed, as shown in Fig. 3, by breaking the joint between the spacing braces 18 and adapting them to assume the position shown in Fig. 65 3, at which time the members 18 are sub-

stantially at right angles to each other. In this condition one of the tie bars 20 of each pair is removed from its pivoted connection upon a complementary member 18 and is attached to a pivot pin mounted upon the 70 lower end of the extension legs 28. The brace members 22, connected with the opposite legs 12, may then be folded and the structure collapsed laterally, at which time the extension legs upon one side are extended to dispose the end bars 13 at an angle and to cause one of the side frame members to be held at the height assumed when making the cot and the opposite side frame member to be elevated to the height assumed 75 in forming the table.

Due to the contracted relation of the two side frames, the pins upon the ends of the frame members are caused to register with other perforations 33 in the end members 13, as shown in Fig. 3. This will cause the canvas to sag and form a comfortable seat. The manner in which the structure may be collapsed is evident. It will thus be seen that I have here provided a simple structure 80 which may be readily folded or converted to form different articles of furniture and will be rigidly maintained in the desired relation to insure a stable structure adapted to meet practical purposes.

Having thus described my invention, what I claim and desire to secure by Letters Patent is—

1. A convertible structure of the type disclosed, comprising a rectangular frame made up of longitudinal side bars and transverse end bars carrying a flexible covering, a pair of transversely spaced supporting legs near each end of the rectangular frame, spacing bars between the legs of each pair near the bottom thereof, whereby the canvas will be held in a horizontal plane, said bars being jointed to permit the transversely spaced legs to be brought together for collapsing 105 the structure, extension pieces on the legs at one side for raising the same to form the back of a settee, the jointed cross-bars then being flexed upwardly into substantially right angular relation to bring the transversely spaced legs closer together, means for shortening the connections between the end pieces and side bars of the rectangular frame, whereby the flexible covering is allowed to sag and form both the bottom 110 and back rest of a settee, and detachable connections between opposite legs at each end for holding them spaced apart in their narrower position.

2. A convertible structure of the type disclosed, comprising a rectangular frame made up of longitudinal side bars and transverse end bars carrying a flexible covering, a pair of transversely spaced supporting legs at each end, spacing bars between the legs of each pair near the bottom thereof, whereby 115

- the rectangular frame will support the canvas horizontally, said bars being jointed to permit the transversely spaced legs to be brought together for collapsing the structure, diagonal brace bars between each leg and adjacent spacing bar jointed for upward folding movement, a hinged connection between the adjacent ends of the spacing bars to prevent the same from assuming 5 a straight line under the thrusts thereon imposed by the brace bars, extension pieces on the legs at one side for raising the same to form the back of a settee, the jointed spacing bars at this time being flexed upwardly into 10 a substantially right angular relation to bring the transversely spaced legs closer together, and means for shortening the connections between the end pieces and side bars of the rectangular frame, whereby the 15 flexible covering is allowed to sag and form both the bottom and back rest of the settee, tie bars assisting to support said brace bars, one end of each of said tie bars adapted to be disconnected from its spacing 20 bar and connected to the lower end of the adjacent extension piece on the supporting legs to hold the opposite legs spaced apart 25 at their lower ends.
3. In convertible furniture, a pair of spaced side bars, a covering carried by the bars, front and rear vertical end supports for the bars, means to allow the end supports to be adjusted so as to vary the space 30 between the side bars, and to also permit the rear supports to be raised up from the ground so as to dispose the rear side bar above the front side bar and the covering in 35 a position to form the back and seat of a settee, and extensible telescopic ground engaging means connected to the front and rear supports to hold the latter in raised position 40 above the ground to form a table, the front extensible means being adapted to be telescoped when the rear extensible means are 45 extended to thereby hold the rear side bar spaced above the front side bar to form a settee.
4. In convertible furniture, a substantially rectangular frame, a covering for the 50 frame, legs for the frame, a breakable connection between the legs whereby to allow the legs to be brought relatively close together, ground engaging extensions for the legs on one side of the frame to support the 55 side bar of said side above the other side and allow the covering to sag to form the back and seat of a settee, and means between the leg extensions and the breakable connections for holding the latter against movement with 60 the legs in their said relatively close relation.
5. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, and means to brace the vertical parts of the breakable connections from the said means for supporting the rear legs. 70
6. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, bracing means between the horizontal parts of the breakable connections and the rear legs extending upwardly at an incline from said horizontal parts and below the covering, and bracing means between the vertical parts of the breakable connections. 75
7. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, and with the horizontal parts below the covering and the vertical parts adjacent to the front legs, and means to hold the breakable connections rigid in their said last-named positions. 80
8. In convertible furniture, side bars, a covering carried by the bars, front and rear legs, breakable connections between the lower ends of the front and rear legs, and means to support the rear legs from the ground and at a distance above the front legs so as to dispose the covering at an incline, said breakable connections in the last-named position of the rear legs having horizontal parts and vertical parts extending downwardly from the horizontal parts. 85
9. In convertible furniture, side bars, extension bars pivotally connected thereto, removable end pieces connecting each pair of extension bars, front and rear legs, break- 90
10. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, and means to brace the vertical parts of the breakable connections from the said means for supporting the rear legs. 95
11. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, bracing means between the horizontal parts of the breakable connections and the rear legs extending upwardly at an incline from said horizontal parts and below the covering, and bracing means between the vertical parts of the breakable connections. 100
12. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, and with the horizontal parts below the covering and the vertical parts adjacent to the front legs, and means to hold the breakable connections rigid in their said last-named positions. 105
13. In convertible furniture, side bars, a covering carried by the bars, front and rear legs, breakable connections between the lower ends of the front and rear legs, and means to support the rear legs from the ground and at a distance above the front legs so as to dispose the covering at an incline, said breakable connections in the last-named position of the rear legs having horizontal parts and vertical parts extending downwardly from the horizontal parts. 110
14. In convertible furniture, side bars, extension bars pivotally connected thereto, removable end pieces connecting each pair of extension bars, front and rear legs, break- 115
15. In convertible furniture, a pair of spaced side bars, a covering carried by the bars, front and rear vertical legs for the bars, breakable connections between the front and rear legs which connections are horizontally disposed when the covering is horizontal, means to support the rear legs at a distance above the surface on which the furniture is mounted and accordingly above the front legs so as to dispose the covering at an incline, said breakable connections in said inclined disposition of the covering having their respective parts arranged horizontally and vertically, and means to brace the vertical parts of the breakable connections from the said means for supporting the rear legs. 120
16. In convertible furniture, side bars, extension bars pivotally connected thereto, removable end pieces connecting each pair of extension bars, front and rear legs, break- 125
17. In convertible furniture, side bars, extension bars pivotally connected thereto, removable end pieces connecting each pair of extension bars, front and rear legs, break- 130

able connections between said front and rear legs and between each of said legs and the adjacent extension bar, and a covering fixedly secured to said side bars and removably mounted to said removable end pieces.

10. In convertible furniture, side bars, extension bars pivotally connected thereto, removable end pieces connecting each pair of extensions, adjusting means for one pair of 10 said extensions, a covering attached to said side bars and said extensions and removably mounted upon said removable end pieces, front and rear legs, breakable connections between said front and rear legs, means to 15 support the rear legs from the ground and at

a distance above the front legs so as to dispose the covering at an incline, means for holding said front legs and said raised rear legs in fixed spaced relation to each other, said last mentioned means including adjustable connections between said removable end pieces and said extension bars. 20

In testimony whereof I have hereunto set my hand in the presence of two subscribing witnesses.
